UNITED STATES PATENT OFFICE.

CAXTON P. RHODES, OF SAN FRANCISCO, AND ARNOLD F. WILLAT, OF SAN RAFAEL, CALIFORNIA.

CIGARETTE HOLDER.

Application filed June 16, 1921. Serial No. 477,882.

To all whom it may concern:

Be it known that we, CAXTON P. RHODES and ARNOLD F. WILLAT, citizens of the United States, and residents, respectively, 5 of the city and county of San Francisco, State of California, and city of San Rafael, county of Marin, State of California, have invented new and useful Improvements in Cigarette Holders, of which the following 10 is a specification.

Our invention refers particularly to the means mounted in the holder for ejecting a cigarette or cigar, which had previously been carried therein, and also to the means 15 by which the ferrule is fixed on the end of said holder. The object of our invention is to provide a holder that will be rigid and serviceable and with ejecting means mounted therein which may be brought into 20 use when desired to eject the cigarette from the holder socket, and which means will remain under spring compression during the time when it is not being used, with all openings closed so that the draft through 25 a cigarette carried in the holder will not be impaired. Also one wherein the slide portion of the ejector means will be released from its spring compression during the 30 ejecting movement so that it will snap to its extreme out position, thus throwing the cigarette butt outward with some force and free from the holder.

Other objects will appear from the drawings and specification.

Fig. 1 is a perspective view of a holder 35 employing our invention.

Fig. 2 is an enlarged cross section of Fig. 1 on the line II—II thereof and with the slide removed therefrom.

Figs. 3, 4, and 5 are longitudinal cross sections of the holder of Fig. 1 taken on the line III—III of Fig. 2, and shown in Fig. 3 the holder prepared for but not fitted with the ejector slide, whereas Fig. 4 shows the 45 slide and ferrule in place and in the retracted position as normally ready for use. In Fig. 5 the ejector is shown pushed forward.

Figs. 6 and 7 are consecutive stages in the 50 flanging of the ferrule, whereas Fig. 8

shows the flange through the completed ferrule.

Figs. 9, 10, 11 are side, rear and plan views of the ejector slide before being placed in the holder.

55

Throughout the figures similar numerals refer to identical parts.

The body of the holder is indicated by the numeral 1 through which there is the well known central tube or opening 2 and 60 the receiving socket end 3. The end of the holder 1 is slotted at 4 and undercut at 5, 6 respectively, whereby a relatively wide slot 4 is formed; and lying parallel thereto and extending through the material is the 65 narrower groove 5, 6 on each side thereof. These grooves form housing walls for the slide 7, ejector 8 and finger member 9. The slide is made with its sides slightly diverging towards the finger member end as shown 70 in the plan view Fig. 11. The purpose of this will be set forth below.

The ejector 8 extends from the slide 7 through the inner groove 4 and projects 75 within the cavity 3 forming a barrier normally near the bottom of the cavity 3 and movable through said cavity to clear the same of a cigarette butt by moving the finger member 9 in an outwardly direction. The normal position of the slide, ejector and 80 finger member are shown in Fig. 4, which is the position of these parts during the time the holder is carrying the cigarette. When

it is desired to eject the cigarette butt the finger member 9 is slid in the direction of 85 the arrow 10 and into the position shown in Fig. 5 when the interior of the cavity will have been fully cleared of the cigarette butt. The slide 7 is normally bent out of a flat plane as clearly shown in Figs. 5 and 90 9 so that when the finger member is moved opposite to the direction of the arrow 10 of Fig. 4, the slide will be distorted from the curved shape in Fig. 9 and constrained to lie flat within the slot 4. It will therefore be held firmly by the friction thus occasioned, and not only will all rattling or looseness be avoided but also it will perform the important function of enabling the finger member to be snapped in the position 95 100

of ejection; that is, the friction due to the spring distortion will first have to be overcome, afterwards the slide will move very quickly snap into the position of Fig. 5, 5 throwing the butt entirely clear of the holder. As a protection and finish to the holder I apply a ferrule, over the end surface 12, the ferrule having an interiorly projecting flange adapted to cooperate with 10 the groove 13 and be held firmly therein.

Referring particularly to Figs. 6, 7 and 8, the body of the ferrule is shown at 14, which is first formed with a feather edge 15 and is then trimmed and bent first into the position 15 shown at 16, and then into the final position shown at 17. A suitable key-way 18 is then cut through the front of the finished ferrule of Fig. 8. The key-way 18 shrouds the extreme end 19 of the slide 7, see Figs. 4 and 9. The parts are assembled by first inserting the complete slide, ejector and finger member of slide 9 into the grooves 4, 5, 6 of the previously prepared holder as shown in Fig. 3. The two sides of the holder 20 are then slightly compressed in the direction of the arrows 20 and 21 of Fig. 2 and the ferrule of Fig. 8 pressed into position over the extreme end 22 of the holder 1, see Figs. 3 and 4. The flange 17 will now fall into the 30 slot and the ferrule will be held firmly in place. The parts now have the appearance shown in Fig. 4 in cross section. In Fig. 5 the finger member 9 has been forced outwardly being guided at such time by the flat 35 spring member 7 moving within the slot 4 and carrying with it the ejector 8 which will now be in the positions shown in Fig. 5. It will be seen that the ferrule of Fig. 8 when being fitted over the end 12 of the 40 holder 1 must either expand or the holder must be compressible; slight compression of about six thousandths of an inch is readily accomplished by pressing the sides together in the direction shown by the arrows 20, 21 of Fig. 2, because of the slots or grooves 5, 6 and the narrow taper end at 19 of the slide 7, see Fig. 11. The slide on its narrow end does not fully fill the groove laterally, except at its rear position, so that when the 45 said slide is in the position shown in Fig. 4 there is a little play between the end 19 on the sides of the groove 5, 6, thus enabling the compression in the direction of the arrows 20, 21, Fig. 2, when the side is in its final position. The fitting of the ferrule of 50 Fig. 8 over the end to complete the assembling of the parts locates and holds the slide in position in the holder.

It will be noticed that the ejector 8 is 55 made bifurcated in a plane at right angles with the axis of the holder (see Figs. 9 and 10). This to enable a cleaner to be thrust through the hole 2 and be clear of the sides of said ejector, for the purpose of cleaning the holder, the ejector being divided on each

side of the cleaner when the latter is being used.

Also the slide 7 and ejector 8 are made in one piece bent over double at 23, and the shank of the finger member 9 is then passed 70 through both thicknesses of the metal as at 24 and riveted or otherwise affixed thereto.

We claim:

1. In a holder for a cigarette or the like, a longitudinal slot extending through the wall of the holder, a trackway on each side of and opening into said slot, a slide movably mounted in said trackway and carrying an inward extending ejector, and a finger member extending through the slot and 75 mounted on the rear end of said slide.

2. A cigarette holder having a receiving cavity comprising the elements set forth in claim 1 wherein said slide is of spring material and resiliently held when retracted 80 within said cavity.

3. A cigarette holder having a receiving cavity and comprising the elements set forth in claim 1 wherein said slide is of spring material and resiliently held when retracted 90 within said cavity, and wherein the sides of said slide are slightly divergent toward the 95 ejector.

4. In a holder having a cavity for receiving cigarettes or the like, a metallic ferrule 100 constructed and adapted to fit over the end of said holder around said cavity and having an annular inwardly projecting flange, a recess in said holder adapted to receive said flange when said ferrule is in final position and a recess across the front of said ferrule adapted to pass an ejector slide.

5. In a holder having a cavity for receiving cigarettes or the like, a metallic ferrule 105 constructed and adapted to fit over the end of said holder around said cavity and having an annular inwardly projecting flange, a recess in said holder adapted to receive said flange when said ferrule is in final position, and a cut through said holder end 110 whereby the holder is compressible to admit the placing of the ferrule.

6. In a holder having a cavity for receiving cigarettes or the like, a metallic ferrule 115 constructed and adapted to fit over the end of said holder around said cavity and having an annular inwardly projecting flange, a recess in said holder adapted to receive said flange when said ferrule is in final position, and a cut through said holder end 120 whereby the holder is compressible to admit the placing of the ferrule and a recess across the front of said ferrule adapted to the passage of an ejector slide.

7. A cigarette holder having a receiving 125 cavity and comprising the elements set forth in claim 1 wherein said slide is of spring material and under distortion when retracted within said cavity, a metallic ferrule constructed and adapted to fit over the end of 130

said holder around said cavity and having an annular inwardly projecting flange, a recess in said holder adapted to receive said flange when said ferrule is in final position and a recess across the front of said ferrule adapted to the passage of an ejector slide.

8. In a cigarette holder, a slide and an ejector struck from a single piece of metal

bent double to form an inner end to said slide and said ejector bent at right angles ¹⁰ therefrom and spaced from said end, and a finger member engaging both thicknesses of metal of the double bend in fixed relation and extending opposite said ejector.
